UNITED STATES PATENT OFFICE.

JOHN ALEXANDER KENNEDY-McGREGOR, OF BIRMINGHAM, AND HARRY WREN, OF BEXHILL, ENGLAND, ASSIGNEES TO HARRY WILLIAM COX, OF NOTTINGHAM, ENGLAND.

ELECTRICAL SWITCH.

No. 841,407.

Specification of Letters Patent.

Patented Jan. 15, 1907.

Application filed August 18, 1906. Serial No. 274,770.

To all whom it may concern:

Be it known that we, JOHN ALEXANDER KENNEDY - McGREGOR, a resident of Birmingham, and HARRY WREN, a resident of Bexhill-on-Sea, England, subjects of the King of Great Britain, have invented certain new and useful Improvements in Electrical Switches, of which the following is a specification.

This invention relates to electrical switches of the quick make-and-break type, and more particularly to improved self-acting means for locking the pivoted bridge or contact-bar in both its open and closed positions.

Referring to the drawings, Figure 1 is a sectional elevation, and Fig. 2 a plan, of a switch constructed according to our invention. Fig. 3 is a sectional elevation showing the bridge in the open position. Fig. 4 is an elevation, and Fig. 5 a plan, of a change-over switch. Fig. 6 is an elevation, and Fig. 7 a plan, showing a bearing-bracket adapted to engage with a stud in the bridge. Fig. 8 is an elevation showing a change-over switch with a bearing-bracket of the same construction as that shown in Figs. 6 and 7.

Like letters indicate like parts throughout the drawings.

According to this invention the pivoted bridge A when in either its open or closed position is rigidly connected or locked to the bearing-bracket D, which carries it, and is disconnected from said bracket or unlocked by a movement of the bridge longitudinally in one direction, while a reverse movement connects or locks it to the bracket again.

The unlocking movement is effected by the operating-lever B, and the locking movement by the quick-action spring C, which serves to connect the bridge A to the operating-lever B in the usual manner.

One end of the bridge A (see Figs. 1 to 3) is mounted on a transverse pivot-pin D', carried by the bearing-bracket D, attached to the base E, and where said pin D' passes through the bridge A the latter is formed with a slot A', as shown in Figs. 1 and 3, so that the said bridge can first be moved longitudinally for a limited distance to release it from the bracket D and then be turned angularly about the said pin D'.

In the form shown in the drawings the bridge A is comprised of two members arranged side by side, and the operating-lever B is mounted loosely on the pivot-pin D', between the members comprising the bridge A, as shown more clearly in Fig. 2.

When either closed or open, the inner end A² of the bridge A engages with an abutment F in the interior of the bearing-bracket D, so that said bridge is normally locked and cannot be moved angularly.

To move the bridge A angularly, it must first be moved longitudinally until its inner end A² is clear of the abutment F. This is effected by the lever B, the side B³ of which engages with a stud or cross-pin A³ in the bridge A when said lever is moved over.

The angular movement of the lever B not only moves the bridge A longitudinally, so as to unlock it, but also extends the quick-action spring C, so that the moment the bridge is unlocked it opens or closes with great rapidity.

The several parts comprising the bridge-locking device may be so disposed that the bridge A is held until the spring C is fully extended, and a quick-action make or break is thus always insured.

In order that the spring C, which, as shown in Figs. 1 to 3, normally lies between the members comprising the bridge A, may be extended to a considerable extent by a limited movement of the lever B, it is connected at C' to a curved part B' of said lever, which part is carried beyond the stud A³ in the bridge A, as shown, and the said stud A³ thus works in the space B² between the curved part B' and the main part of the lever B.

In addition to the abutment F stops F' and F'', projecting from the inner faces of the cheeks of the bracket D, may be provided for stopping the bridge A when it reaches either of its extreme positions.

In order to move the bridge A from the closed position (shown in Figs. 1 and 2) to the open position, (shown in Fig. 3,) the lever B is moved over so as to extend the spring C, and at the same time the side B³ on the said lever engages with the stud A³ and moves the bridge A longitudinally in the direction indicated by the arrow in Fig. 1 until its inner

end A^2 is clear of the abutment F . As soon as this takes place the bridge A will first be moved by the spring C into the open position (shown in Fig. 3) and then by a reverse longitudinal movement be returned to its locking position again, the end A^2 of the bridge A now engaging with the other side of the abutment F , as shown in Fig. 3.

In closing the switch the action of the lever B and bridge A is in each case precisely the same as when opening it.

The spring C serves a dual purpose—that is, it moves the bridge A over quickly and returns it into engagement with the bracket D on the completion of the first movement.

Should the spring C fail to act, the bridge A may be positively withdrawn from the contacts G or replaced by the lever B , acting on the stud A^3 .

In the change-over switch (shown in Figs. 4 and 5) the bracket D is provided with two locking-abutments F , (see Fig. 4,) one on each side, so that the bridge A may be placed in three positions. In this case the operating-lever is comprised of two side members B^4 , which are approximately of the same shape as the lever B B' , previously described. These side members B^4 are mounted on the pivot D' on the outer sides of the bracket D , and their outer free ends are connected at B^5 , so as to form practically one lever. The ends of the stud A^3 are with this arrangement extended so as to engage with the sides B^3 of the opening B^2 in each of the side members B^4 comprising the lever. Two springs C are preferably provided in this case, and they are situated between the members B^4 and the bridge A , as shown.

The inner end A^2 of the bridge A when closed engages with either the abutment F on the right or left, according to whether the bridge is on the left or right of the bracket D , and when open it engages between both of said abutments.

In the switch shown in Figs. 6, 7, and 8 the bearing-bracket is formed so as to engage with the stud A^3 in and hold the bridge. In this case the cheeks of the bracket D are formed with notches J , (see Fig. 6,) so disposed that the ends of the stud A^3 in the bridge A can take into said notches. The action of the switch is in this case precisely the same. The longitudinal movement of the bridge A moves the stud A^3 out of said notches, and when moved by the spring C from one point to another the stud A^3 rides on the concentric surface of the cheeks of the bearing-bracket D and drops into the next notch. In the change-over switch shown in Fig. 8 three sets of notches J are provided, as shown, so that the bridge A may be placed in either of three positions.

The bridge-locking abutment F and stops F' F'' (shown in Figs. 1 to 5) may, if desired, be employed in connection with the bearing-

bracket D . (Shown in Figs. 5 and 6.) The employment of the two sets of devices is more particularly applicable to switches for carrying heavy currents, in which the bridge is very heavy, and the sudden stopping of the same is liable to damage the pivot D' or the slot A' in the bridge A .

In the arrangement shown and described there are no spring-controlled catches or catch-pins which must be moved relatively to the bridge in order to effect the unlocking and locking of the same, and the moving parts are reduced to the lowest possible number—that is, two, the bridge A and lever B or B' . There is thus less liability of its getting out of order and failing in its action. One spring C is also made to perform two offices—that is, to give the quick action to the bridge A and at the same time move it longitudinally in the reverse direction to the lever B or B' and effect the locking of said bridge.

What we claim as our invention, and desire to secure by Letters Patent, is—

1. In an electrical switch, the combination of a pivoted bridge mounted so that it can be moved longitudinally, a bearing-bracket for the same adapted to engage with and hold the bridge, an operating-lever adapted to engage with and move the bridge longitudinally out of engagement with the bearing-bracket, and a spring connection between the bridge and operating-lever so disposed as to give a quick action and then return the bridge into engagement with the bearing-bracket, substantially as described.

2. In an electrical switch, the combination of a bridge provided with a stud or cross-pin and a slot to admit the pivot-pin, a bearing-bracket for the same adapted to engage with the bridge, an operating-lever adapted to engage with the stud in the bridge and move it longitudinally out of engagement with the bearing-bracket, and a spring connected to the bridge and an arm of the operating-lever respectively so disposed as to give a quick action and then return the bridge into engagement with the bearing-bracket, substantially as described.

3. In an electrical switch, the combination of a pivoted bridge provided with a stud or cross-pin and mounted so that it can be moved longitudinally, a bearing-bracket for the same provided with notches to admit the stud in the bridge, an operating-lever adapted to engage with the stud and move the bridge longitudinally out of engagement with the bearing-bracket and a spring connected to the bridge and an arm of the operating-lever respectively so disposed as to give a quick action and then return the bridge into engagement with the bearing-bracket, substantially as described.

4. In an electrical switch, the combination of a pivoted bridge provided with a stud or

cross-pin and a slot to admit the pivot-pin, a bearing-bracket for the same provided with notches to admit the ends of the stud in the bridge, an operating-lever adapted to engage with the stud in the bridge and move it longitudinally out of engagement with the bearing-bracket, and a spring connected to the bridge and an arm of the operating-lever respectively so disposed as to give a quick action and then return the bridge into engagement with the bearing-bracket, substantially as described.

In testimony whereof we have signed our names to this specification in the presence of two subscribing witnesses.
